UNITED STATES PATENT OFFICE.

JAMES A. NICOLETTI, OF BROOKLYN, NEW YORK.

DESIGN FOR A COMBINED ASH RECEIVER AND MATCH HOLDER.

Application filed January 2, 1925. Serial No. 11,857. Term of patent 7 years.

To all whom it may concern:

Be it known that I, JAMES A. NICOLETTI, a citizen of the United States of America, residing at Brooklyn, in the county of Kings and State of New York, have invented a new, original, and ornamental Design for Combined Ash Receiver and Match Holder, of which the following is a specification, reference being had to the accompanying drawing, forming a part hereof.

The figure is a perspective view showing my new, original and ornamental design for combined ash receiver and match holder.

I claim:

The ornamental design for a combined ash receiver and match holder as shown.

JAMES A. NICOLETTI.
